UNITED STATES PATENT OFFICE.

JOIIN R. S. YODER, OF FREEMANSBURG, PENNSYLVANIA.

DESIGN FOR A BUTTONHOLE-OPENER.

SPECIFICATION forming part of Design No. 33,159, dated September 4, 1900.

Application filed July 31, 1900. Serial No. 25,469. Term of patent 7 years.

To all whom it may concern:

Be it known that I, JOHN R. S. YODER, a citizen of the United States, residing at Freemansburg, in the county of Northampton and State 5 of Pennsylvania, have invented and produced a new and original Design for a Buttonhole-Opener, of which the following is a specification.

This invention relates to a design for a buttonhole-opener; and the leading feature of the same consists in the design forming the subject-matter of the accompanying illustrations, in which—

Figure 1 is a perspective view of a buttonhole-opener embodying the design. Fig. 2 is 15 a side elevation of the same. Fig. 3 is a section on the line 2 2, Fig. 1.

The design is characterized by the main or body portion 1, of solid elongated heart shape, having a reduced neck 2 between the same 20 and an open heart-shaped head 3, the latter having a greater transverse extent than the former.

Having thus described the invention, what is claimed as new is—

The design for a buttonhole-opener, herein shown and described.

In testimony that I claim the foregoing as my own I have hereto affixed my signature in the presence of two witnesses.

JOIIN R. S. YODER.
